Fig. 2.

Diagram illustrating the control circuit for a Weston Meter (M1) and two motors (MOT.1, MOT.2). The circuit is powered by a 50~ source. Key components include:

- Weston Meter (M1):** Connected in series with R4 and R5. R4 is connected to the 50~ source. R5 is connected to ground.
- Resistors (R1-R9):** R1, R2, R3, R6, R7, R8, and R9 are connected in various branches of the circuit.
- Capacitors (C1-C5):** C1, C2, C3, C4, and C5 are used in conjunction with resistors to form time constants or filter circuits.
- Control Components:**
  - Relays:** V1, V2, V3, and V4.
  - Solenoids:** S1, S2, S3, S4, and S5.
  - Limit Switches:** L1, L2, L3, L4, and L5.
  - Motors:** MOT.1 and MOT.2.
  - Panel Lamps:** Indicated by a dashed box labeled "PANEL LAMPS".
- Power Supply:** A 40V source is connected to the circuit, with a switch REC-1 and a resistor R9.
- Output:** The circuit is connected to a 50~ source, with terminals T1, T2, T3, and T4.

ELECTRONIC DENIER CONTROL

John S. Seney, Henrico County, Va., assignor to
 E. I. du Pont de Nemours and Company, Wil-
 mington, Del., a corporation of Delaware

Application June 7, 1950, Serial No. 166,750

5 Claims. (Cl. 74—395)

1

This invention relates to an improved speed control for spinning machines, such as viscose rayon spinning machines, to produce finished yarn of more uniform denier. More particularly, this invention is concerned with the spinning of viscose rayon on a bobbin spinning machine and with an electronic control of the machine drive shafts to effect improved results.

In the manufacture of regenerated cellulose yarn by the viscose process, provisions are made for varying the rate of draw-off and/or pump delivery to produce in its finished form a yarn of more uniform denier and dyeability than could be provided in the absence of these corrective changes. In the bobbin spinning process as the yarn cake builds up and the peripheral lay of the yarn becomes greater and greater, the rotational speed of the bobbin must be diminished. Because of variations in shrinkage that arise throughout the bobbin package this diminution in rotational speed should be other than a straight line compensation and numerous mechanical arrangements have been proposed and used with varying degrees of success.

The mechanical compensators used are dependent on "constant speed" drive motors and generally the pump shaft speed is assumed to be at a constant R. P. M. and the pump delivery therefore constant, whereas there are sometimes variations of as much as 5% in the spinning solution delivery and not infrequently denier variation in the finished yarn may be as much as 7% above or below the stated denier or an overall variation as much as 14%.

It is, therefore, an object of this invention to provide more accurate control of the driving elements to maintain the denier more nearly constant and to provide means for compensatively altering the rate of yarn draw-off should variations in pump delivery arise. Other objects will be apparent from the description that follows.

The objects of this invention are accomplished by synchronizing the bobbin speed and pump speed plus the desired speed variable included on the cam through the use of an electronic circuit in which changes in bobbin speed are made to effect proportional changes in pump speeds, or vice versa. Briefly, this invention is accomplished by having in a balanced or balanceable relationship two tachometer generators or one tachometer generator and a constant voltage source of direct current electricity e. g. a battery. Where two tachometer generators are used one is directly connected to the bobbin drive shaft and one is directly connected to the pump shaft

2

and so wired and controlled through a cam operated variable resistance that the desired proportional speeds of these two shafts are maintained. The electrical connections and details of construction and operation are shown in drawings listed below and explained hereinafter. While the invention is described with particular reference to viscose spinning, the apparatus can be applied to the spinning or extrusion of any synthetic yarn.

In the drawings:

Figure 1 is a flow sheet showing the control apparatus of this invention in simplified form;

Figure 2 is a detailed electrical wire diagram of the control apparatus shown in Figure 1;

Figure 3 is a side elevation of the cam operated variable speed controller;

Figure 4 is a plan view of the apparatus shown in Figure 3 and

Figure 5 is taken on line 5—5 of Figure 3.

Referring to Figure 1, G-1 is a tachometer generator attached to the bobbin shaft drive (connection not shown) and G-2 is a tachometer generator attached to the shaft driving the viscose pump or pumps (connection not shown). These generators are connected so that the negative connection 70 is common to each. The voltage output of each generator is proportional to the speed of the shaft to which each is connected and in the electrical circuit shown no current flows when the output of the generators is the same.

Connected in parallel with generator G-1 are resistance potentiometers R-2 and R-3. A highly accurate indicator for tachometer G-1 is provided as follows:

As shown in Figure 1, a bias voltage is obtained from REC-1, a selenium rectifier, and this D. C. voltage is applied across R-9. The negative connection of REC-1 is connected to the common negative terminal 70 of G-1. The slider 40 of R-9 can then be set to produce the necessary exact biasing voltage to the tachometer indicator M-1. A resistor R-3 is connected across the output of G-1 so that any ratio of the voltage developed by G-1 can be obtained between the slider 50 of R-3 and the common negative terminal 70 of G-1. Connected between slider 50 of R-3 and the tachometer indicator M-1 is a variable series resistor R-4. This provides a fine adjustment to the tachometer indicator. To illustrate, assume G-1 is turning 140 R. P. M. and slider 50 at R-3 is set midway of R-3 and slider 40 at R-9 is so adjusted that M-1 reads 0 R. P. M. If G-1 is speeded up to 200 R. P. M., it will show full scale

of the tachometer indicator meter provided R-4 has been properly set for this particular meter movement and the meter M-1 will show only speeds above 140 R. P. M. and no more than 200 R. P. M. Meter M-1 has a scale which will be magnified in increments of 1 R. P. M. between the speeds of 140 to 200 R. P. M.

The output of G-1 is connected across potentiometer R-2 and that of G-2 is connected across the resistor R-6. Resistor R-2 is the high speed control voltage divider and it applies the desired voltage from G-1 to input transformer T-4. Resistors R-5 and R-8 are connected in series and shunt the slider contact 10 of R-6 to the common negative junction 10 of G-1 and G-2. The resistors R-5, R-6 and R-8 control the voltage output from G-2 to transformer T-4. Transformer T-4 has dual input and between it and the electrical bridge comprising R-5, R-6 and R-8 is a converter CON-1 which is a single pole double throw switch operating in synchronism with the line voltage furnished by T-1 S-1 through connections X-Y (see Figure 2). This switch is polarized by a permanent magnet, so that one of the contacts will always be closed during the negative half cycle of the supply voltage from S-1 T-1 and the other contact will be closed during the positive half cycle. Any flow of current due to a difference in potential between slider contact 20 of R-2 and 30 of R-8 is converted from direct current to a proportional 60 cycle alternating current by the converter CON-1 and transformer T-4.

Transformer T-4 acts as a phase shifting and coupling device between the bridge circuit and the electronic voltage amplifier 80. The phase of the output voltage at S-6 depends on the polarity of the voltage from sliders 20 and 30 at R-2 and R-8, respectively. After conversion, the A. C. voltage output is amplified by a conventional electronic amplifier hook-up 80 (shown in detail in Figure 2). The motor MOT-3 is a two phase control motor. It is a brushless, reversible, variable speed induction motor of the drag cup type. MOT-3 is connected, as described below, to the control screw 91 of the bobbin drive P. I. V. (see Figure 4). "P. I. V." is the generally accepted designation for a positive-drive, infinitely variable speed changer, one type being disclosed in U. S. Patent No. 2,076,202 at page 2, column 1, line 60. Depending upon the amount of voltage and the polarity of the current, MOT-3 changes the speed of the bobbins and since tachometer generator G-1 is attached to it, it changes also the speed of G-1 and the amount of its output.

In order to control denier or mass per unit length of the yarn spun, the amount of viscose or other spinning solution must be taken into account. As stated, tachometer generator G-2 is attached directly to the metering pump shaft (not shown) of the spinning machine and furnishes voltage to one side of the network. The slider contact 30 at R-8 is operated by cam 35. The movement of cam 35 is controlled by synchronous motor MOT-1, which drives this cam on the electronic circuit or, when this is off, mechanically operates the P. I. V. control screw. The compensating voltage coming from R-8 is then changed as required. From this, it can be seen that the ratio of yarn windup to pump delivery will at all times stay constant, provided the cam is made for straight line compensation.

The electronic circuit can be seen in more detail by reference to Figure 2 and to the following discussion. With generators G-1 and G-2

connected as shown and turning at a given speed and with slider contact 20 of R-2 set at a certain point, a voltage, for example, 1 volt, is obtained between the negative common connection 10 and the slider contact 20 of R-2. The slider contact 10 of R-6 is set to obtain a positive potential of 1 volt between it and the common negative connection 10. If slider contact 30 of R-8 is set at the extreme upper position as shown in Figure 1, the 1 volt potential is also obtained at the contact 30. With a 1 volt potential at contact 20 and at contact 30, no current would flow between these points. If the speed of a generator, say G-1, changes for example, from 1 volt to 2 volts, there would exist a difference in potential and current would flow between contacts 20 and 30.

This current is converted to 60 cycle A. C. by CON-1 and transformer T-4. The A. C. voltage output is amplified by a conventional electronic amplifier hook-up through tubes V-1, V-2 and power amplifier V-3. The amplifier is supplied direct current from rectifier tube V-4 and S-2 T-1. The amplified current is supplied to MOT-3 by power amplifier tube V-3. The other motor winding is continuously energized by line voltage from S-4 T-2. The phase of the current coming from V-3 determines the direction of rotation of MOT-3 and its amplitude determines the speed of the motor.

With G-2 turning at a constant rate to produce 1 volt between 10 and 30 and G-1 now producing 2 volts, the slider 20 at R-2 becomes of a positive (+) polarity and the slider 30 of a negative (-) polarity. In view of the negative voltage, MOT-3 will rotate in a direction to slow down the bobbin because it is driving the control screw of the bobbin P. I. V. Since G-1 is attached to the bobbin drive, MOT-3 will operate in the slow down direction until the voltage difference between the sliders at 20 and 30 is eliminated. At this point the entire network is in balance.

If G-1 produced a smaller voltage than G-2, say 0.5 volt, a difference of 0.5 volt would exist between sliders 20 and 30 of the opposite polarity. Slider 30 at R-8 would be plus and slider 20 at R-2 would be negative in polarity. MOT-3 would run in a reverse direction raising the speed of the bobbins and, hence, G-1 until zero voltage difference again was attained. Thus, if the speeds of G-1 and G-2 are not the same, MOT-3 will bring about the change needed to keep the network in balance.

With this in mind R-5 is so adjusted that a voltage drop is effected across R-8 equal to the desired speed change of G-1 or the bobbin windup speed. Assuming that G-1 develops 2 volts at 200 R. P. M. and 1.5 volts at 150 R. P. M., R-5 is so adjusted that 0.5 volt is the drop across R-8. The voltage at slider 10 of R-6 will be set to produce 2 volts between it and the common negative connection. With the above stated conditions the voltage between the sliders 20 at R-2 and 30 at R-8 will be 0, provided that G-1 is turning 200 R. P. M. Now if slider 30 is moved from its top position (Figure 1) so that it is at the other end of R-8, there will be a voltage difference of 0.5 volt. In order for there to be 0 volt between sliders 20 and 30, G-1 will have to turn at 150 R. P. M. Since MOT-3 keeps the voltage between sliders 30 and 10 at 0, then by changing the position along resistance R-8 of its slider the bobbin speed can be changed from 200 R. P. M. to 150 R. P. M. At the start of the spin cycle before the bobbins begin to build up

yarn, G-2 will be generating 2 volts. If for some reason it does not rotate sufficiently to do this, but say 1.99 volts, MOT-3 reduces the speed of G-1 or the bobbins so that G-1 produces only 1.99 volts.

The movement of contact 30 to vary the resistance of R-8 involves a mechanical unit containing certain electrical switches which relate the movement of contact 30 to the change needed to keep the network in balance over the desired speed pattern. This unit is shown in Figures 3, 4 and 5.

The entire unit is mounted on a frame 47. Shaft 4 is a drive shaft connected to the bobbin drive P. I. V. by sprockets and chain 5. A plate or support member 2 is mounted so that it can pivot about shaft 4. This plate 2 has attached to it gears 17, 18, 38, 13, 39 and cycle cam 35, cam follower 36, and slider 30 in contact (not shown, see Figure 1) with R-8. The unit 88 bolted to plate 2 supports cam follower 36, rack 42, gear 45 and one end of spring 86.

Mounted on the stationary frame 47 is shaft 63 which is connected to and driven by MOT-3, the electronic control motor. Attached to shaft 63 is gear 16 which drives gear 18 when the latter is in the position shown. Gear 18 in turn drives gear 17. Since gear 17 is attached to shaft 4 which in turn is attached to the bobbin P. I. V. control screw, shaft 63 driven by MOT-3 controls the bobbin P. I. V. drive or the speed at which the bobbins are driven.

Also mounted on frame 47 is shaft 64 which is driven by cycle timer motor MOT-1. This drives gear 12 which in turn drives gear 13 (mounted on pivotable plate 2) when gear 13 is in the position shown in Figure 5. Gear 13 drives gear 38 through gear 39 and gear 38 drives cycle cam 35 in a clockwise direction. As this cam rotates it moves cam follower 36, which bears roller 37 resting on the periphery of cam 35, in an outwardly direction. Cam follower 36 has on one side a rack, designated as 42 in Figure 5. This rack turns gear 45 which is attached to slider contact 30 and the resistance at R-8 is changed accordingly. Thus, MOT-1 drives cam 35 which through cam follower 36 changes the compensating voltage coming from R-8.

At the start of a new spinning cycle the operator turns reset switch actuator 54 to the reset position and holds it there until the machine is set to high starting speed. MOT-2 starts up driving shaft 62 and since plate 2 is connected to it by shifter link 93, plate 2 is made to pivot around shaft 4. As plate 2 moves switch actuator 34 eventually causes microswitch B to open and this stops MOT-2 and keeps it stopped as long as the operator holds the reset switch actuator 54 in the reset position. The pivoting of plate 2 to this reset position has caused gear 18 to go out of mesh with gear 16 and gear 12 to go out of mesh with gear 13. The speed reset hand wheel 55 attached to shaft 4 is free to turn and the operator turns it to set the bobbin speed at the start of the spinning cycle or 200 R. P. M. Cam reset spring 23 also causes cam 35 to return to the start position; cam stop 28 comes back to rest on the stop or shock absorber 29 (see Figure 4). Slider 30 of R-8 is returned by spring 86 to its start position. Now the machine has been reset and the operator allows reset switch actuator 54 to assume its normal position. This by-passes switch B and MOT-2 starts up again; the bearing 2 pivots so that the gears mesh momentarily and then go out of

mesh and it continues to pivot until microswitch A is opened. This stops MOT-2. Gears 16 and 18 now mesh as do gears 12 and 13. MOT-3 is now driving the control screw to the P. I. V. and the timing motor MOT-1 is advancing the cycle cam 35 through its compensating cycle.

In addition to the foregoing, provision may be made to reduce the bobbin speed automatically by a straight line speed reduction by MOT-1 in the event of failure of the electronic system. This is done automatically by having connected, as shown in Figure 2, between the sliders 30 at R-8 and 20 at R-2 a sensitive, normally-open relay CR-4 which is connected and set to close if more than 2 micro amperes flow between the sliders of R-8 and R-2 (indicating that the electronic system is failing because current in this circuit should always be near zero if the system is in balance).

Assuming that the electronic control is failing and CR-4 has closed its control contacts, circuit is made from the line voltage neutral through the closed contact of CR-4 to trip out warning light L-5 and to coil of CR-2 through normally closed contacts of reset switch G to the other side of the line. This, of course, energizes CR-2 opening contacts 5 and 6 of CR-2 and closes 5 and 4. This reverses timer motor MOT-1. Contacts 1 and 2 of CR-2 open and 2 and 3 close. This applies line voltage through normally closed reset switch G through contacts 2 and 3 of CR-2 through normally closed switch C to reset motor MOT-2 to the other side of the line. Reset motor MOT-2 starts up and shifts plate 2 so that gears 12 and 18 engage thus connecting the P. I. V. control screw with timer motor MOT-1 whereby MOT-1 reduces the bobbin speed at a constant rate. Limit switch C is opened by pin 94 thereby stopping MOT-2 with gears 12 and 18 in mesh. CR-3 is provided to energize CR-2 when the electronic control unit is removed from service for repair. The switch C is a normally closed switch and is operated by pin 94 which is keyed to MOT-2 and is fixed to open switch C when gears 18 and 12 are in mesh or when MOT-1 is in control of the drive. A jumper is installed in plugs P-12A and P-12-12 which keep CR-3 energized as long as these plugs are in place. The removal of either will de-energize CR-3 thereby energizing CR-2, placing the compensator on straight line compensation. Thus, if the electronic control fails for some reason, the rotational speed of the bobbins will be diminished in accordance with the cake build-up.

Upon the resetting of CR-4, CR-2 drops out again reversing MOT-1 energizing MOT-2 through reset limit A. Plate 2 then opens reset limit A when gears 16 and 18, and 12 and 13 are again in mesh. When the reset switch is operated, current flows to reset motor MOT-2 from normally closed contacts of reset switch F (see Figures 2 and 3) through doff limit switch B thus running MOT-2 until B contact is opened by actuator 34 attached to plate 2. In this position gears are neutralized for the reset and upon the release of reset switch to MOT-2, switch G again closes and starts MOT-2 so that the proper gearing is again engaged at gears 16 and 18 and at gears 12 and 13. If relay CR-2 is energized the P. I. V. will be operated from the timer motor MOT-1. If CR-2 is dropped out, the P. I. V. will be driven from the electronic control motor MOT-3.

In order to prevent CR-4 closing while the machine is being reset a relay CR-1 is energized by

the voltage applied to the doffing roll motor. (This motor must be running during the doffing operation but it is turned off as soon as the machine is reset and restrung.) The normally closed contacts opened by CR-1 disconnect the relay CR-4 from the system thus preventing its accidental action during the reset operation. In order to prevent the P. I. V. control screw from being turned past its limits, limit switches E and D are connected in series with the supply voltage to MOT-3 and MOT-4.

In some instances, as for example, in bucket spinning or even bobbin processes, a constant voltage supply such as a battery may be used in place of G-2. It is, of course, recognized that the draw-off device may be a wind-up such as a bobbin or it may be simply a roller such as a godet.

By means of this invention excellent uniformity in yarn denier is obtained. The variation in denier is no more than $\frac{1}{4}$ of 1 per cent or on 1200-denier yarn ± 3 denier, which makes the yarn admirably suited for any purpose. In the case of fine denier yarn, such as 100 denier, the normal variation resulting from this control is scarcely measurable being of the order of $\frac{1}{4}$ denier.

While the invention has been described in terms of denier control, it may, of course, be used in connection with any sort of desired compensation. For instance, to improve dyeing uniformity throughout the spin package or to produce yarn having greater uniformity in any one property or a better average uniformity of a number of properties, such as elongation, tenacity or other physical properties that may be affected advantageously by altering the proportional rate of spinning solution delivery and yarn draw-off.

The invention is applicable to any type of spinning machine such as bucket or yarn advancing reel collections or other continuous yarn production methods as well as the bobbin collection method. It may be used to advantage not only with regenerated cellulose yarn produced by the viscose process but also any coagulating bath spinning process or to dry spun or melt spun yarns of any description. For example, cuprammonium cellulose yarn, cellulose ester yarns, cellulose ether yarns, polyvinyl yarns, such as polyvinyl chloride, polyvinyl acetate, polyacrylonitrile, nylon, polyester yarn, etc.

Any departure from the procedure described herein which conforms to the principles of the invention is intended to be included within the scope of the claims below.

I claim:

1. Apparatus for controlling the speed of one driven shaft relative to the speed of a second independently driven shaft which comprises a pair of tachometer generators connected in series opposition and arranged to be driven respectively at speeds proportional to the speed of said first shaft and the speed of said second shaft, a resistance network connected to receive the uni-

directional output of said generators, an amplifier circuit including converter means responsive to amplitude and direction of flow of current in said resistance network for providing an alternating current output signal of proportional magnitude and of a phase related to the polarity of said output, and speed control means responsive to the output signal of said amplifier and adapted to vary the relative speeds of said shafts in accordance with said magnitude and phase until said output signal is nullified as the result of corresponding changes in the speeds of said generators.

2. Apparatus as defined in claim 1 in which said speed control means includes a reversible, variable-speed induction motor connected to a control screw of a positive-ininitely-variable drive connected to one of said shafts.

3. Apparatus as defined in claim 1 in which a resistor in said resistance network is continuously adjusted by a cam driven by a cycle time motor, thereby varying said output signal and causing the relative speeds of said shafts to change as a function of time in a predetermined manner.

4. In apparatus for controlling the speed of one driven shaft relative to the speed of a second independently driven shaft by the action of a motor adapted to change the speed ratio of said shafts in response to an error signal derived through an electrical control circuit from tachometer generators connected in series opposition and arranged to be driven at speeds proportional to the respective shaft speeds, the improvement comprising relay means responsive to an excessive value of said error signal indicative of abnormal functioning of said control circuit and operative to disconnect said motor and to replace it by means for reducing the speed of said first shaft gradually until it stops to prevent uncontrolled driving of said first shaft.

5. The apparatus improvement defined in claim 4 in which said first shaft is driven through a positive-ininitely-variable drive having a control screw and the means for reducing the speed of said shaft comprises a timer motor connected to said screw to rotate it so as to reduce the speed of said shaft at a constant rate.
